UNITED STATES PATENT OFFICE.

EMILE AUGUSTIN BARBET, OF PARIS, FRANCE.

DISTILLING AND RECTIFYING COLUMN.

1,427,430.

Specification of Letters Patent. Patented Aug. 29, 1922.

Application filed September 22, 1920. Serial No. 411,924.

To all whom it may concern:

Be it known that I, EMILE AUGUSTIN BARBET, a citizen of the French Republic, residing at No. 5 Rue de l'Échelle, Paris, France, 5 have invented certain new and useful Improvements in and Relating to Distilling and Rectifying Columns, of which the following is a specification.

Among the many types of plates which 10 have been proposed for distilling and rectifying columns, the plates with hoods have the property of remaining filled with the liquid during a temporary stopping of the operation, and they are very much appreciated owing to this property.

In contradistinction thereto, the old perforated plates of the Savalle type are emptied as soon as the operation stops but they have the advantage of a better working 20 owing to a very high division of the bubbles.

It has been tried to combine the advantages offered by the two types of plates and to form non-emptiable although perforated 25 plates, but difficulties of construction were met with. The problem is still more difficult in the case when it is desired to provide cooling coils immersed into the reflux liquid of the plates.

30 The present invention relates to an improved column-plate consisting essentially of a solid disc and of a certain number of long hoods parallel to each other, the borders of which are provided with horizontal perforated plates.

On the other hand it has been possible to drive away all the liquid from underneath the said perforated plates by slightly stamping the column-plate underneath them in 40 such a manner as to form a double incline which leaves only a sectional passage which is strictly indispensable for the circulation of the steam.

The column-plate is thus provided with a 45 series of sharp edges on which are supported and fixed the edges of the perforated plates.

The accompanying drawing illustrates the plate.

Fig. 1 is a plan view, the left hand side of 50 the figure showing the hoods in position whilst in the right-hand side of the figure the said hoods have not been shown.

Fig. 2 is a section along X—X in Fig. 1 with all the hoods placed in their position.

55 Figure 3 is a plan of a hood formed in

relatively fragile material such as ceramic ware or Volvic lava, while

Figure 4 is a view in section showing the hood in position over the chimney of a plate formed in the like material. 60

As shown in the drawing, the column-plate A is stamped in such a manner as to present a certain number of longitudinal sharp edges B (four of these edges are illustrated), the length of which is limited by 65 that of the hoods.

At both ends, a plane surface is provided with an overflow C and with a dish D respectively. Horizontal surfaces are left between the inclined surfaces, provided with 70 chimneys E on which long hoods F are fixed in any suitable manner. Perforated plates G are fixed to the said long hoods, and on the sharp edges B on which they are held in position; the sides of the hoods and the projections of the edges are so dimensioned that the plates G shall be horizontal. The chimneys E, instead of being round, may be of an elongated shape and may be formed by bending up the metal which forms the bottom 75 of the column-plate.

In the type which has been illustrated as having four sharp edges, there are three long hoods and, an elongated, sector-shaped hood is arranged on each side so as to use 80 the whole of the surface of the column-plate and to prevent any passage of liquid to the periphery.

The working of the column-plate according to the present invention can be easily 90 understood; the vapours coming from the lower column-plate pass through the chimneys E underneath the hoods F and drive the liquid contained between the bottom A and the plates G, through the perforations 95 with which the latter plates are provided, pass themselves through the plates G and bubble into the liquid of the column-plate in a finely-divided state. As that section of the column-plate comprised between two sharp 100 edges gradually decreases to the right and to the left of the axis of the hood the vapours can drive easily the liquid which is contained in the space between the bottom of the column-plate and the plates G above 105 the latter plates.

It will be noticed that the column-plate according to the present invention has the advantages of the perforated column-plates without having their drawbacks, because if 110

the pressure falls inside the column, the liquid of the column-plate does not fall on the lower column-plate but on the bottom A; it forms therefore a non-emptiable column plate.

The said arrangement of overflows, the latter having preferably an elongated form, ensures a good circulation and an equal distribution of the liquid to the four perforated paths.

It has been said at the beginning of the present application that in certain cases it is advantageous to arrange a cooling coil on the column-plates; nothing easier when a column-plate according to the present invention is used; owing to the shape of the hoods it is possible to arrange without any difficulty a coil H going along each hood on each side thereof and resting on the perforated plates on which it is easy to fix it by means of a simple copper wire passing through the holes of the perforated plate. Moreover, in a prior patent of applicant dated the 6th February 1920 for Great Britain and the 25th February 1920 for the U. S. A. and relating to "improvements in condensation in rectifying apparatus", the reflux of the cooling liquid is used in the cooling coils of the plates; this method of operation can be applied to the column-plates according to the present application.

A perforated plate made of copper would not withstand a long time in distilling columns, in which the liquid is always somewhat acid; the holes would be enlarged gradually and the working of the apparatus would be disturbed. It will be then easy to use instead of plates made of laminated copper, perforated plates made of gun-metal or phosphor bronze.

It is also possible to use plates made of porcelain or earthenware.

There are cases in which the acidity of the liquids renders necessary the use of columns made either of ceramic ware, or of Volvic lava. The long hoods would be too fragile in that case and it will be preferable to use round hoods as shown in Figs. 3 and 4 (plan and section). The round hood is made in one piece with its flat circular collar.

As to the column-plate, its flat bottom is slightly stamped downwards underneath the hood in such a manner as to provide a section for the passage of the steam which gradually decreases from the centre to the periphery as shown in Fig. 1.

It is possible to weld the hoods to the column-plate.

For column-plates made of lava, the thickness of which is always at least 5 centimeters, the carving underneath the hoods will be made by means of a chisel, the thickness of the column-plate being thereby reduced and the hood will be sealed either by means of sulphur, or by means of a cement formed of silicate of soda and asbestos powder.

What I claim is:—

1. An improved column plate for distilling and rectifying apparatus, comprising a plate, elevations in the plate, chimneys extending from the plate between such elevations, in an upward direction to a point above the level of the elevations, hoods over the chimneys and foraminous surfaces extending from the hoods and resting upon the elevations.

2. An improved column plate for distilling and rectifying apparatus, comprising a plate, a plurality of parallel elevations extending substantially across the plate, chimneys extending from the plate between said elevations to a point above the level of the elevations, elongated hoods arranged over the chimneys in each of the portions of the plate between the said elevations, and perforated plates connecting adjacent hoods and resting on the elevations.

3. An improved column plate for distilling and rectifying apparatus, comprising a plate, a plurality of parallel elevations, extending substantially across the plate, chimneys extending from the plate between said elevations to a point above the level of the elevations, elongated hoods arranged over the chimneys in each of the portions of the plate between said elevations, perforated plates connecting adjacent hoods and resting on the elevations, and cooling coils on the perforated plates.

4. An improved column plate for distilling and rectifying apparatus, comprising a plate, a plurality of elevations in the form of angular ridges extending substantially across the plate, chimneys in the plate between said elevations, elongated hoods extending longitudinally in relation to the elevations and covering the chimneys and horizontally perforated plates extending between adjacent hoods and resting on the angular ridges.

In testimony whereof I have signed my name to this specification.

EMILE AUGUSTIN BARBET.
